UNITED STATES PATENT OFFICE.

EDWIN I. NOTTINGHAM, OF WASHINGTON, DISTRICT OF COLUMBIA.

DESIGN FOR A BADGE.

SPECIFICATION forming part of Design No. 18,468, dated July 17, 1888.

Application filed June 16, 1888. Serial No. 277,377. Term of patent 3½ years.

To all whom it may concern:

Be it known that I, EDWIN I. NOTTINGHAM, a citizen of the United States, residing at Washington, District of Columbia, have invented 5 and produced a new and original Design for a Campaign-Badge, of which the following is a specification, reference being had to the accompanying drawing, which represents my design.

The predominant feature of my design consists in the arrangement of the United States colors displayed on a strip or field, a bandana handkerchief below the stars and stripes, and two medallions containing portraits.

In my design, as shown in the drawing, the 15 section A exhibits the stars and stripes in the form of a shield suspended from a bar or pin, E, adapted to bear a legend. The section B exhibits a fac-simile of a bandana handkerchief with spots a thereon arranged as a bor-

der row, and the lower edge of the handkerchief is ornamented with fringe b. Superimposed upon the stars and stripes and bandana handkerchief are two medallions, C D, containing portraits, their adjacent edges being in contact, the edge of the lower one, D, as 25 shown. The two medallions may have portraits and other names impressed thereon.

I claim as my invention—

A design for a badge, consisting of a body divided into two sections, one section having 30 thereon stars and stripes and the other section the representation of a bandana handkerchief, the said sections having medallions containing portraits, as set forth.

EDWIN I. NOTTINGHAM.
